UNITED STATES PATENT OFFICE

JOSEF F. PALME, OF ELIZABETH, NEW JERSEY, ASSIGNOR TO THE SINGER MANUFACTURING COMPANY, OF ELIZABETH, NEW JERSEY, A CORPORATION OF NEW JERSEY

SEWING MACHINE

Application filed January 7, 1931. Serial No. 507,075.

This invention relates to sewing machines, more particularly of the type having laterally vibrating needle and loop-taking devices adapted for the formation of zigzag stitches, and has for an object to reduce the number of working parts and otherwise simplify and improve the needle-bar and loop-taker vibrating mechanism of the machine disclosed in the patent to A. Grieb, No. 1,197,735, of Sept. 12, 1916, while maintaining ample room under the gooseneck of the machine for the accommodation and passage of the work.

The invention comprises the devices, combinations and arrangements of parts herein-after more particularly described and pointed out in the claims.

The features of the invention and the advantages attained thereby will be readily understood by those skilled in the art from the following detailed description of a preferred embodiment of the invention illustrated in the accompanying drawings, in which Fig. 1 is a side elevation of a sewing machine embodying the invention. Fig. 2 is a horizontal section through the gooseneck of the machine, showing the bed and bed-mechanism in plan. Fig. 3 is a section substantially on the line 3—3, Fig. 1. Fig. 4 is an end elevation of the machine looking from the left of Fig. 1 and Fig. 5 is a section on the line 5—5, Fig. 1.

The machine is formed with a frame having a bed 1 and an overhanging gooseneck 2 including the upright member or standard 3 and overhanging arm 4 terminating in the head 5.

Pivotedly mounted on the stud 6 fixed to the head 5 is the vibratory needle-bar-carrier 7 having upper and lower bearings, 8 and 9, respectively, for the reciprocating needle-bar 10 carrying the needle 11.

The needle-bar is reciprocated by means of the usual link-connection 12 with the needle-bar actuating lever 13 fulcrumed at 14 on the gooseneck 2 and connected at its rear end to the pitman 15 which is actuated by the eccentric 16 on the main-shaft 17 journaled in the bed 1; the constructive features 50 so far described being substantially in ac-

cordance with the disclosure of the Grieb patent previously referred to.

The feeding mechanism of the machine includes the usual four-motion feed-dog 18 which cooperates with the usual presser-foot 55 19 and is actuated by any suitable mechanism, preferably that disclosed in the Grieb patent referred to.

Cooperating with the needle 11 is the loop-taker 20, preferably in the form of the well known rotary chain-stitch-looper having the usual loop-seizing beak 21 and loop-spreading wing 22. The looper is secured to the looper-shaft 23 which is journaled in the looper-carrier or sleeve 24 slidably mounted 60 in the bearing-bushing 25 in the bed 1. The sleeve 24 is formed at one end with a block-shaped head 26 to which is secured by the screw 27 one end of the needle-throat member 28 slidably mounted in the fixed guide-way 29 and formed at its free end with a needle-aperture 30. The connection of the sleeve 24 with the needle-throat member 28 through the sleeve-head 26 fixes the sleeve 24 against rotation in the bushing 25 and 65 maintains the aperture 30 and the looper 20 in fixed operative relation to one another. Fixed to the end of the looper-shaft 23, remote from the looper 20, is the coupling collar 31 formed with the diametrical slot 32 70 which is entered by the flat tongue 33 formed on the end of the main-shaft 17. The tongue-and-slot connection between the looper-shaft 23 and the main-shaft 17 transmits rotary 75 motion from the main-shaft to the looper 20 while permitting the looper and throat-plate assembly 24, 26, 28 to be vibrated or reciprocated laterally of the line of feed.

Rigidly secured to the needle-bar-carrier 7 by screws 35 is one end of the arm 36 which 80 is gooseneck shaped and roughly parallels the frame-gooseneck 2, i. e., the arm 36 has an upper laterally extending portion 36' and a downwardly extending portion 36''; the arm 36, as a whole, being bowed away from 85 the line of feed so as to provide space under the arms 2 and 36 for the accommodation and passage of the work. The downwardly extending portion 36'' of the arm 36 may be 90 slidably received in the slot 37 of the bracket 95 100

38 fixed to the bed 1 so as to be steadied by such bracket. The arm 36 has connected to it, by means of the screw 39 adjacent its lower end and below the level of the pivot-stud 6, one end of a link 40, the other end of which is connected by the screw 41 to the arm 42 fixed by means of the screws 43 to the head-block 26 of the sleeve 24. The link 40 connects the needle-bar- and looper-carriers together and causes them to move in unison laterally of the line of feed.

To actuate the connected needle-bar- and looper-carriers 7 and 24, there is connected to the arm 36 by the screw 44 below the level of the pivot-stud 6, one end of the link 45, the opposite end of which is adjustably connected to the slotted arm 46 of a rock-lever fulcrumed at 47 on the frame of the machine and having a downwardly extending arm 48 which carries a roller 49 entering the cam-slot 50 in the barrel-cam 51 which is journaled to rotate on the stationary shaft 52 fixed to the bed-lug 53. The barrel-cam 51 has a gear-toothed portion 54 which meshes with the pinion 55 fixed to the main-shaft 17. The ratio of gearing between the pinion 55 and the gear 54 is as one is to two; the cam 51 rotating at one-half the speed of the main-shaft 17. The cam 50 is so shaped as to vibrate the needle and looper laterally of the line of feed and hold them in their extreme positions while the needle is penetrating the work and presenting its loop to the loop-taker; the lateral shift being effected while the needle is out of the work. The throw or extent of lateral vibration of the needle and looper may be varied by adjusting the upper end of the link 45 along the slot in the arm 46. The slot in the arm 46 is curved in the arc of a circle about the screw 44 as a center when the needle and looper are in their mid-position, in which position the needle-bar is vertical. By adjusting the link 45 into alinement with the centers 44 and 47, the lateral vibratory movements of the needle and looper may be practically eliminated, in which position of adjustment the machine may be used for straight-away sewing.

It will be seen in Fig. 1 that the pivot-point 39 for the link 40, being below the pivot-stud 6 has both a vertical and a horizontal component of motion, the latter of which is transmitted by the link 40 to the looper-carrier 24 which is moved simultaneously with and in the same direction laterally of the line of feed as the needle 11.

Having thus set forth the nature of the invention, what I claim herein is:

60 1. In a sewing machine, in combination, feeding mechanism, a pivotally mounted needle-bar-carrier, a looper-carrier movable laterally of the line of feed, an arm rigidly secured at one end to said needle-bar-carrier and connected at its other end to said looper-

carrier, said arm being bowed between its ends away from the line of feed, and means for vibrating said arm.

2. In a sewing machine, in combination, feeding mechanism, a pivotally mounted needle-bar-carrier, a looper-carrier movable laterally of the line of feed, an arm rigidly secured at one end to said needle-bar-carrier and connected at its other end to said looper-carrier, said arm being bowed between its ends away from the line of feed, and means for vibrating said arm, said other end of said arm being below the level of the pivot-point of the needle-bar-carrier.

3. In a sewing machine, in combination, feeding mechanism, a pivotally mounted needle-bar-carrier, a looper-carrier movable laterally of the line of feed, an arm rigidly secured at one end to said needle-bar carrier, a link connected between the other end of said arm and said looper-carrier, said arm being bowed between its ends away from the line of feed, and means for vibrating said arm.

4. In a sewing machine, in combination, feeding mechanism, a pivotally mounted needle-bar-carrier, a looper-carrier movable laterally of the line of feed, an arm rigidly secured at one end to said needle-bar-carrier and connected at its other end to said looper-carrier, said arm being bowed between its ends away from the line of feed, and means for vibrating said arm, said other end of said arm being below the level of the pivot-point of the needle-bar-carrier, said means including a rocking member and a link connected at one end to said rocking member and at its other end to said arm, said link having its point of connection with said arm below the level of the pivot-point of said needle-bar-carrier.

5. A sewing machine having a frame formed with a gooseneck, a vibratory needle-bar-carrier mounted at the free end of said gooseneck, a gooseneck-shaped arm roughly paralleling the frame-gooseneck and rigidly secured at one end to said needle-bar-carrier, a looper-carrier connected to said gooseneck-shaped arm, and means for vibrating said arm.

6. A sewing machine having in combination, a frame formed with a bed and an overhanging gooseneck, feeding mechanism, a needle-bar-carrier fulcrumed on said gooseneck to vibrate transversely of the line of feed, a reciprocating needle-bar in said carrier, a needle carried by said needle-bar, a loop-taker cooperating with said needle and mounted in said bed for movement laterally of the line of feed, an arm rigidly secured at one end to said needle-bar-carrier and having its free end terminating below said gooseneck and adjacent said bed, said arm being bowed in the same direction as the bend of said

gooseneck, a connection between the free end of said arm and said loop-taker to cause the latter to vibrate laterally of the line of feed in harmony with said needle, and means for vibrating said needle and loop-taker.

5 In testimony whereof I have signed my name to this specification.

JOSEF F. PALME.
